UNITED STATES PATENT OFFICE.

LAURENCE E. TOPHAM, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

SHOE MACHINE.

Original application filed April 9, 1917, Serial No. 160,751. Divided and this application filed December 11, 1923. Serial No. 679,899.

This invention relates to shoe machines and more particularly to machines for sewing the outsole to the welt of a welted shoe. Certain features of the invention, however, are not limited to use in this class of machines but may be embodied in machines for sewing other parts of a shoe or in machines for performing operations other than sewing upon a shoe.

10 The several features of the present invention are particularly applicable to machines in which the shoe and the means for operating upon the shoe are moved relatively to transfer the point of operation about the shoe and 15 to change the relative positions of the shoe and the operating means to present the shoe properly to the operating means as the point of operation is transferred about the shoe, and in which the shoe is supported in operating position in the machine and all of its 20 movements are effected and controlled by automatically acting mechanisms.

Except as defined in the claims, however, the several features of the present invention 25 are not limited to machines which are wholly automatic in character but may be embodied in machines in which certain of the movements of the shoe are imparted by the operator or in machines in which the shoe is held 30 and manipulated by the operator.

The object of the present invention is to improve the construction and mode of operation of shoe machines of the character above referred to, and with this object in view the 35 invention consists in the constructions, combinations and arrangements of parts herein-after described and particularly pointed out in the claims, the advantages of which will be understood and appreciated by those skilled in the art from the accompanying drawings illustrating a machine embodying the invention in its preferred form and the following detailed description of the construction therein shown.

45 In the drawings Fig. 1 is a view in front elevation of a machine embodying the invention; Fig. 2 is a view in side elevation of the machine, looking from the right; Fig. 3 is a plan view of the machine; Fig. 4 is a view in vertical section, looking from the left, illustrating the driving and stopping mechanism of the machine; Fig. 5 is a view in horizontal section, taken substantially on the line 5-5 of Fig. 1; Fig. 6 is a view in front elevation, partly broken away and 55 partly in section, illustrating particularly certain parts of the driving and stopping mechanism for the machine; Fig. 7 is a view in side elevation illustrating the parts of the sewing mechanism; Fig. 8 is a detail 60 view in side elevation illustrating a portion of the mechanism shown in Fig. 7; Fig. 9 is a detail plan view, partly in section, illustrating particularly parts of the sewing mechanism and parts of the driving and 65 stopping mechanisms; Fig. 10 is a detail sectional view taken substantially on the line 10-10 of Fig. 9; Fig. 11 is a detail view in front elevation illustrating the edge gage 70 mechanism and the feed changing mechanism; Fig. 12 is a view in side elevation of the mechanism shown in Fig. 11, looking from the right; Fig. 13 is a detail plan view illustrating particularly the mechanism for driving the pattern cam shaft; Fig. 14 is a detail in side elevation, looking from the 75 left-hand side of the machine, illustrating the mechanism for driving the battern cam shaft; Fig. 15 is a detail view in front elevation illustrating certain parts of the mechanism for stopping the machine during or at the completion of the sewing of a seam; Fig. 16 is a plan view of the mechanism illustrated in Fig. 15; Fig. 17 is a detail 80 view in rear elevation, partly in section, illustrating certain parts of the mechanism for stopping the machine and certain parts associated therewith; Fig. 18 is a sectional view taken substantially on the line 18-18 of Fig. 17; Fig. 19 is a detail view in front elevation, partly in section, illustrating certain parts of the mechanism for stopping the machine and for lifting the presser foot at the completion of the sewing of a seam; Fig. 20 is a sectional view taken substantially on the line 20-20 of Fig. 19; and Figs. 21, 22, 23 and 24 are detail plan views illustrating in different positions the mechanism for 85 stopping the machine, Figs. 21 and 23 each showing the parts adjusted for the sewing of a right shoe and respectively showing the positions of the parts upon stopping the machine as the pattern cam shaft is brought to starting position, and upon stopping the machine at the completion of the sewing of a seam, and Figs. 22 and 24 each showing the parts adjusted for the sewing of a left shoe and respectively showing the positions 90 of the parts upon stopping the machine.

- of the parts upon stopping the machine as the pattern cam shaft is brought to starting position, and upon stopping the machine at the completion of the sewing of a seam.
- 5 The machine illustrated in the drawing is an automatic shoe machine, the mechanism for operating upon the shoe of which consists of a sewing mechanism constructed and arranged for sewing outsoles to the welts of welted shoes. This machine is fully illustrated and described in applicant's pending application Ser. No. 160,751, filed April 9, 1917, of which the present application is a division.
- 15 The illustrated machine comprises, in addition to the sewing mechanism, a jack upon which the lasted shoe is placed by the operator preparatory to the sewing of a seam, means for supporting the jack constructed and arranged to permit a movement of the jack and shoe in the direction of feed to transfer the point of operation about the shoe and a movement transversely of the direction of feed to maintain the edge of the shoe bottom in the proper lateral relation to the stitch forming, work holding and work feeding devices of the sewing mechanism, mechanism for moving the jack to change the position of the shoe with relation to the devices for operating on the shoe to present the shoe properly to said devices as the point of operation is transferred about the shoe bottom, means for driving the sewing mechanism and said jack moving mechanism during the sewing of the seam, devices for stopping the machine at the completion of the sewing of a seam, means for driving said jack moving mechanism independently of the sewing mechanism to bring the jack to starting position, and devices for stopping the machine when the jack has been brought to starting position.
- 25 The sewing mechanism of the machine illustrated in the drawing, with the exception of certain changes in the pul-off mechanism hereinafter described, is substantially the same in construction, arrangement and mode of operation of parts as that of the Goodyear rapid lockstitch machine for sewing outsoles, illustrated and described in the patent to French & Meyer, No. 473,870, dated April 26, 1892. This mechanism (see Figs. 1 and 7) comprises a curved hook needle 2, a work feeding awl 4, a shuttle 6, a take-up 8, an auxiliary take-up 10, a thread-locking device 12, a pull-off 14, and a tension device 16. The machine is also provided with a work support 18 and a presser-foot 20. The parts of the sewing mechanism are driven from a series of cams mounted upon a cam shaft 22 which for the sake of convenience in the following description will be termed the sewing cam shaft.
- 35 For the sake of clearness in the explana-

tion of certain features of the invention, certain parts of the sewing mechanism and the mechanisms for actuating these parts are described in this application. For a full and complete description of the parts not described herein, reference may be had to the French & Meyer patent referred to above. The awl 4 (see Figs. 7, 8, 9 and 10) is mounted upon an awl carrier 24 pivoted upon a stud 26 mounted in a bearing in an upright 28 carried by the feed slide 30. Secured to the feed slide is a bracket 32 carrying a stud 34 upon which is pivoted a lever 36. Pivoted upon the lever 36 is a block 38 engaging in a curved groove 40 in the forwardly projecting arm of a lever 42 pivoted upon a stud 44. The rearwardly projecting arm of this lever carries a cam roll 46 engaging in a cam groove in a cam disk 48 mounted on the sewing cam shaft 22. During the rotation of the sewing cam shaft the lever 42 is oscillated by the action of the cam groove in the cam disk 48 on the cam roll 46, and through the connection of the feed slide with the forwardly projecting arm of the lever 42 the feed slide is reciprocated in its guides in the frame. By adjusting the lever 36 about the stud 34 the distance of the block 38 from the axis of oscillation of the lever 42 may be varied to give the desired length of feed. In order to enable the operator accurately to position the lever 36 to give a predetermined length of feed a scale plate 50 is mounted on the frame of the machine and is provided with a series of perforations 52 in which stop pins 54 may be inserted to limit the movements of the lever.

The auxiliary take-up consists of a roll mounted upon a lever 56 pivoted on the frame. This lever is acted upon by a spring 58 which tends to maintain the lever in an elevated position in engagement with an adjustable stop pin, but allows the roll to yield to give thread during the loop drawing stroke of the take-up.

The pull-off comprises a roll mounted upon a forwardly extending arm 60 fixed to one end of the rock shaft 62 mounted in bearing in the frame. An upwardly extending arm 64 fixed to the other end of the rock shaft 62 carries a pivotally mounted block 66 which engages in a groove 68 in an oscillating lever 70 pivoted at 72 on the vertically movable support 74. The support 74 is pivotally mounted at 76 upon a rearwardly extending arm of the presser-foot lever 78 which is pivoted upon a stud 80 mounted in the frame of the machine. The lower end of the support 74 is formed with guides embracing a block 82 pivoted on the rock shaft 62, the block serving as a guide for the lower end of the support. A spring 84 is arranged to act on the support 74 and normally tends to lift the support to main-

tain the presser-foot in yielding engagement with the work. The lever 70 is oscillated through certain connections from a cam lever actuated by a cam carried by the sewing cam shaft 22 of the machine, as will be hereinafter described.

The presser-foot 20 is mounted upon the forward end of the lever 78. The presser-foot mechanism also comprises an arm 86 pivoted upon the stud 80, which carries the presser-foot lever and extending rearwardly from its pivotal point above the rearwardly extending arm of the presser-foot lever. A rod 88 is pivotally connected at its lower end to the rearwardly extending arm of the presser-foot lever and passes through a lateral projection 90 on the arm 86. A sleeve 92 is mounted on the rod above the projection 90 and a coiled spring 94 surrounding the rod is interposed between the upper end of the sleeve and a nut 96 threaded on the upper end of the rod. The rear end of the arm 86 is formed with a series of teeth adapted to be engaged by a pawl 98 pivoted at 100 upon a cam lever 102. This lever is pivoted at 104 upon the frame and carries a cam roll 106 for engagement with a cam groove in a cam disk 108 mounted on the sewing cam shaft 22. The pawl 98 is yieldingly engaged with the teeth on the rear end of the arm 86 by means of a leaf spring 110 mounted on the lever 102. The rear end of the presser-foot lever is formed with a series of teeth which are adapted to be engaged by a locking pawl 112 pivoted at 114 on the frame. This pawl is yieldingly engaged with the teeth on the end of the presser-foot lever by means of a leaf spring 116 mounted on the lever 102. In order to throw out the pawls during each cycle of operations the pawl 98 is formed with a shoulder 118 which engages a pin 120 on the frame, and the lever 102 is formed with a projection 122 for engagement with a projection 124 on the pawl 112. During the feeding of the work the pawls 98 and 112 are disengaged respectively from the teeth on the rear end of the arm 86 and on the rear end of the presser-foot lever 78, the presser-foot then being held lightly in engagement with the work by the tension exerted by the spring 84. After the work has been fed and before the needle retracts from the work, the arm 86 is lifted by the action of the cam lever 102 through the pawl 98, thereby compressing the spring 94 and causing the presser-foot to engage the work with considerable pressure, after which the presser-foot is locked in position by the action of the pawl 112 and remains locked during the remainder of the cycle of operations.

The jack upon which the lasted shoe is supported during the sewing operation (see Figs. 1 and 2) comprises a spindle 126 and a jack frame secured to the upper end of

the spindle provided with a toe support 128 and with a heel supporting last pin 130. The jack spindle is rotatively mounted in a supporting frame 122 which is pivotally mounted so as to swing about a horizontal axis in a yoke 134 formed at the forward end of a rod 136. The rear end of the rod 136 is connected by a swivel joint to a shackle block 138 which embraces a yoke 140 and is pivotally connected therewith to swing in a vertical plane by means of bearing pins 142. The yoke 140 embraces a link frame 144 (see also Fig. 13) and is pivotally connected with the link frame to swing in a horizontal plane by means of bearing pins 146. One end of the link frame 144 is connected by vertically arranged pivot pins to a horizontally arranged supporting arm 150 and the other end of the link frame is similarly connected to a horizontally arranged supporting arm 152. The supporting arms extend in opposite directions and at their outer ends are pivotally mounted upon the frame of the machine. A slide block 154 is mounted upon the rod 136 and is connected with the yoke 140 by a link 156. Pivotally connected with the slide block 154 is a rod 158 extending at its lower end through a sleeve mounted upon trunnions engaging in bearing in an arm 160 on the yoke 140. Surrounding the rod 158 is a coiled spring 162 interposed between a collar fixed to the rod and the upper end of the sleeve.

The jack supporting structure above described permits a movement in the direction of feed of the upper end of the jack to transfer the point of operation about the shoe and a movement transversely of the direction of feed to keep the edge of the shoe in the proper lateral relation to the sewing mechanism, as well as a bodily vertical movement. Also movements of the jack are permitted to change the position of the shoe during the sewing operation to place the portion of the shoe at the point of operation in the proper position with relation to the sewing mechanism as the point of operation is transferred about the shoe. These movements consist of lateral and longitudinal tipping movements about axes extending in the general direction of the length of the shoe and transversely of the shoe to bring the shoe bottom at the point of operation into the proper plane, and lateral turning movements to bring the marginal line of the shoe bottom at the point of operation into the proper position with relation to the line of feed. The tipping movements are imparted by devices acting on the jack supporting spindle to move the lower end of the spindle forwardly and rearwardly and back and forth at right angles to the forward and rearward movement, and the turning movements are imparted by devices acting on the spindle to rotate the spindle.

Because of the fact that the shoe is held at all times at the point of operation by the needle and the awl and by the work support and the presser foot, the tipping and turning movements are caused to take place about the point of operation, the shoe being tipped and turned about these work engaging devices as a fulcrum.

The movement of the shoe, and of the jack upon which it is supported, to transfer the point of operation about the shoe, is produced by the action on the shoe of the feeding devices of the sewing mechanism. As the point of operation is transferred along the shoe, mechanism acting on the jack spindle tends yieldingly to swing the upper end of the jack towards the rear of the machine and thus to keep the edge of the shoe sole between the work support and the presser foot of the sewing mechanism. This mechanism comprises a pulley or disc 164 fixed to the jack spindle and a pair of cables 166 and 168 passing in opposite directions about the pulley and each attached at one end to the pulley. These cables extend rearwardly from the pulley 164 respectively over pulleys 170, 172 and then forwardly and are respectively connected at the ends to tension springs 174 and 176, which springs are attached at their forward ends to pins mounted in the frame of the machine. These springs also, because of their connections through the cables 166 and 168 with the pulley 164 fixed to the jack spindle, tend to rotate the jack spindle. Mechanism fully described in application Ser. No. 160,751, is provided for controlling the tension exerted by each of these springs which will operate to vary the tension at different points in the sewing operation.

The tipping and lateral turning movements are imparted to the jack through suitable connections from a cam shaft 178 which, for the sake of convenience, will be hereinafter termed the pattern cam shaft. This cam shaft is rotated through less than a complete revolution during the sewing of a shoe and then its rotation is completed while the sewing mechanism remains at rest to bring the shaft to the proper position for the start of the next operation upon another shoe. To permit the same cams to be used in sewing both right and left shoes, the machine has provision whereby the cam shaft may be rotated in either direction. The same set of connections is employed for imparting the lateral tipping movements to the shoe in sewing either a right or a left shoe. On account of the reversal in the direction of rotation of the cams, however, two sets of connections are provided for imparting the longitudinal tipping movements to the shoe and two sets of connections for imparting the turning movements to the shoe, one set of connections being used

in sewing a right shoe and the other set being used in sewing a left shoe.

The lateral tipping movements of the shoe are produced by the forward and rearward swinging movements of the arm 150 which, through the connections described between the arm and the lower end of the jack spindle, impart forward and rearward movements to the lower end of the spindle. The swinging movements of this arm are produced by means of a cam roll 180 mounted on the arm and engaging a cam groove in a cam disk 182 mounted upon the cam shaft 178.

The mechanism for imparting the longitudinal tipping movements to the shoe employed in sewing a right shoe comprises a lever 184 pivoted upon a vertical shaft 186 and connected by a link 188 to the lower end of the jack spindle. The lever 184 is provided with arms upon which is mounted a segmental plate 190 formed with a notch adapted to be engaged by the upper end of a latch pivotally mounted in one arm of a lever 192 pivoted upon the shaft 186 and having its other end engaging a cam groove in the cam disk 182. For imparting the longitudinal tipping movements to the shoe when a left shoe is being sewn a similar set of levers and links is provided comprising a lever 194 pivoted upon a vertical pivot shaft 196 and connected at its forward end with the lower end of the jack spindle by means of a connecting rod 198. The rear end of the lever 194 is connected by means of a link 200 to a lever 202 pivotally mounted upon the vertical shaft 186 and provided with a notched segmental plate adapted to be engaged by the lower end of the latch mounted in the cam lever 192.

The mechanism for imparting the turning movements to the jack spindle to turn the shoe laterally during the sewing of a right shoe comprises a circular rack or internal gear segment 204 pivotally mounted upon the spindle carrying frame 132 and meshing with a gear upon the spindle. The gear segment is connected by means of a rod 206 to one arm of a bell crank 208 pivotally mounted upon the lever 184. The other end of the bell crank 208 is connected through a link 210, T-shaped lever 212 and link 214 to a lever 216 pivotally mounted upon the shaft 186. This lever 216 is provided with a notched segmental plate 218, similar to the notched segmental plate 190, adapted to be engaged by a latch mounted in one arm of a lever 220. This lever is pivotally mounted upon the shaft 186 and is engaged by a cam groove in a cam disk 222 secured to the cam shaft 178. A similar set of connections are provided for imparting the turning movements to the jack spindle to turn the jack laterally when a left shoe is being sewn, these connections comprising a bell crank 224

pivotedly mounted upon the lever 194 and having one of its arms connected to the gear segment 204 by a link 226. The other arm of the bell crank 224 is connected by a link 228 to one arm of a bell crank 230, the other arm of which is connected by a rod 232 to a lever 234 pivotally mounted upon the pivot shaft 186. This lever is provided with a segmental notched plate 236 adapted to be engaged by the lower end of the latch mounted in the cam actuated lever 220.

The specific construction and arrangement of the several parts of the jack tipping and turning mechanism above referred to are 15 fully illustrated and described in application Ser. No. 160,751.

During the sewing of a seam the pattern cam shaft 178 is driven from the sewing cam shaft 22. The mechanism for driving 20 the pattern cam shaft (see Figs. 1, 2, 3 and 13) comprises a gear 238 attached to the pattern cam shaft and a spiral gear 240 meshing with the gear 238. The spiral gear 240 is journaled on and held from movement 25 longitudinally of a shaft 242 which is slidably mounted in bearings in sleeves 244 and 246, which sleeves are respectively journaled in bearings in the frame of the machine. The sleeve 244 carries at one end a bevel gear 248 and the sleeve 246 carries at one 30 end a bevel gear 250, these gears each meshing with an intermediate bevel gear 252 secured to the lower end of a vertical shaft 254 arranged in alignment with the counter shaft 35 of the driving mechanism hereinafter described, but capable of being rotated independently of said shaft. The bevel gears 248 and 250 thus rotate in opposite directions. The spiral gear 240 is provided with 40 a series of clutch projections formed on one end of the gear for engagement with the clutch projections formed on the bevel gear 248 and upon its opposite end the spiral gear 240 is provided with a second series of 45 clutch projections for engagement with the clutch projections formed on the bevel gear 250. When the spiral gear 240 is clutched to the bevel gear 248 the pattern cam shaft will be driven in a right hand or clockwise 50 direction (Fig. 13), which is the direction of rotation imparted to the cam shaft when a right shoe is being sewn. When the spiral gear 240 is clutched to the bevel gear 250 the cam shaft will be driven in a left 55 hand or counter-clockwise direction, which is the direction proper for sewing a left shoe. In order that the spiral gear 240 may be shifted longitudinally to clutch, the same either to the bevel gear 248 or to the bevel 60 gear 250 the shaft 242, upon which the spiral gear is mounted, is arranged for longitudinal movement in its bearings in the sleeves 244 and 246. When changing from a right shoe to a left, or from a left shoe to a 65 right, the operator shifts the shaft 242 longi-

tudinally to reverse the direction in which the pattern cam shaft 178 is driven before the machine is started. The mechanism provided for shifting the shaft comprises a block 256 secured to one end of the shaft 70 242, a rod 258 threaded into the block and having a pair of spaced projections 260 extending laterally therefrom, a lever 262 pivoted on the shaft 264 and having an arm 266 carrying a pin 268 engaging between 75 the projections 260 and a second arm 270, and an operating lever 272 pivotally mounted in a recess in the arm 270. During the sewing operation the bevel gears 248 and 250 are driven by the rotary movement of 80 the sleeve 246. The mechanism for driving the sleeve 246 comprises a ratchet wheel 274 secured to the outer end of the sleeve and a pair of pawls 276 and 278 pivoted, respectively, at 280 and 282 upon an oscillating 85 pawl carrier 284. The pawls 276 and 278 are connected by a tension spring 286 which maintains the acting ends of the pawls in engagement with the teeth on the periphery of the ratchet wheel. The acting ends or 90 tooth engaging projections on the pawls face in the same direction and the pawls cooperate to impart rotary movement to the ratchet wheel during the oscillation of the pawl carrier. The mechanism for oscillating the pawl carrier 284 comprises an actuating lever 288 having its forward end pivotally connected to the pawl carrier. The lever 288 is pivotally mounted at 290 upon the upper end of the link 292, which is 95 pivoted at 294 upon a pivoted support 296 adjustably mounted to swing upon an axis substantially parallel with the pivotal connection between the upper end of the link 292 and the lever 288. The rear end of the 100 lever 288 is pivotally connected to the lower end of a link 298, the upper end of which is pivotally connected to the rear end of the cam lever 300. The cam lever is mounted upon a pivot shaft 302 and carries at its 105 forward end a cam roll engaging in a cam groove in a cam disk or wheel 304 mounted on the sewing cam shaft.

The driving mechanism for the machine (see Figs. 2, 3, 4 and 5) comprises a shaft 115 306 upon which is mounted a fast pulley 308 and a loose pulley 310. This shaft carries a bevel gear 312 which meshes with a bevel gear 314 mounted on the upper end 120 of a vertical countershaft 316. Fixed upon the shaft 316 is a disk 318 carrying the driving member 320 of a friction clutch. The driven member 322 of the clutch is carried by a flange extending outwardly from a sleeve 324 loosely mounted upon the 125 countershaft 316. The sleeve 324 also carries a spiral gear 326 meshing with a spiral gear 328 formed on a sleeve 330 mounted on the sewing cam shaft 22 to rotate therewith. During the sewing operation the 130

members 320 and 322 of the main friction driving clutch are engaged and the sewing cam shaft 22 is driven through the spiral gears 326 and 328 at a speed depending upon the speed of the driving shaft 306.

To enable the members of the main driving clutch to be engaged and disengaged, the sleeve 324 which carries the driven member of the clutch is arranged to slide longitudinally of the shaft 316 upon which it is mounted to engage and disengage the clutch. The spiral gear 326 is formed with a cylindrical recess, as shown in Fig. 4, the upper face of which is engaged by a ball thrust bearing 332 interposed between said face and the upper end of a sleeve 334 mounted on the shaft 316, and in a bearing on the frame to slide longitudinally of the shaft. The upper end of the sleeve 334 is formed with a flange 336 which is adapted to engage an inwardly projecting flange 338 on a collar 340 threaded into the recess in the spiral gear 326. The sleeve 334 is moved upwardly by the operator upon starting the machine to actuate the sleeve 324 to engage the members of the main driving clutch, and is automatically moved downwardly upon stopping the machine. During the downward movements of the sleeve the flange 336 on the sleeve engages the flange 338 on the collar 340, and moves the sleeve 324 downwardly to disengage the members of the main driving clutch. The collar 340 provides an adjustable connection between the sleeve 334 and the sleeve 324.

To enable the collar to be turned readily to adjust the same in the recess in the spiral gear 326 the collar is formed with a series of openings 342 in which may be inserted any suitable tool for turning the collar. The collar when adjusted is held in adjusted position by means of a pin 344 mounted in the spiral gear, the lower end of which is adapted to engage in any one of a series of recesses 346 in the collar. The pin is acted upon by a spring 348 attached to the spiral gear and bearing upon the head of the pin which holds the lower end of the pin in engagement with the recess in the collar.

The mechanism by which the sleeve 334 is actuated to cause the engagement and disengagement of the main driving clutch, (see Figs. 4, 5, 6, 15, 16 and 17), comprises a disk 350 carried at one end of, and preferably formed integral with a sleeve 352 mounted in a bearing 354 in the frame of the machine, said disk having a series of teeth 356 meshing with a series of teeth 358 formed on the exterior of the sleeve 334. To the opposite end of the sleeve 352 is clamped an arm 360 to the outer end of which is connected by means of a stud 362 a hollow cylinder 364. Through this cylinder passes a rod 366 pivotally connected at one end by a stud 368 to an arm of a lever 370 keyed to one end of a shaft 372 mounted to turn in the sleeve 352.

Surrounding the rod 366 within the cylinder 364 is a coiled spring 374 which at its lower end engages the lower end wall of the cylinder and at its upper end acts against a collar 376 held by a stop nut 378 upon the rod, the collar being arranged to slide in the upper end of the cylinder. This spring furnishes a yielding connection between the arm 360 and the lever 370. Upon the opposite end of the shaft 372 is mounted a carrier 380 formed with a dove-tailed guide in which is mounted a dove-tailed slide 382. The slide is yieldingly held in elevated position in the carrier 380 by a coiled spring 384 attached at its upper end to a pin 386 secured in the carrier and, at its lower end to a pin 388 secured in the slide. Projecting forwardly from the slide 382 is a stud 390 carrying a roll 392 which engages in an irregularly shaped inclined slot 394 formed in a bracket 396 secured to the frame of the machine. This roll also engages in an irregularly shaped slot 398 formed in an arm 400 pivoted upon a stud 402 projecting from a lever 404. The lever 404 is provided with a pivot stud or shaft 406 mounted in bearings in the frame of the machine, and is normally held in elevated position by means of a coiled spring 408 attached at its lower end to a pin projecting from a stud 410 formed integral with the lever 404, and at its upper end to a pin 412 mounted on the frame of the machine. The lever 404 is provided with an operating arm 414 terminating in a handle. In starting the machine, the operator seizes the handle of the operating arm 414 and swings the lever 404 downwardly from the position shown in Fig. 6 to that shown in Fig. 15. The arm 400, through its engagement with the roll 392, depresses the roll and the slide 382 upon which it is carried, the roll moving downwardly through the slot 394 in the bracket 396, which acts as a guide for the roll. The lower end of the carrier 380 will thus be swung to the left (Figs. 6 and 15) in starting the machine, and through the connection between the carrier and the disk 350 the disk will be turned in a direction to elevate the sleeve 334 to engage the members of the main driving clutch. When the sleeve 334 has been elevated by the movement of the carrier sufficiently to engage the members of the clutch, the spring 374 will yield during the continued movement of the carrier, and the members of the clutch will be held yieldingly in engagement through the action of the spring. In order to retain the members of the main driving clutch in engagement until the sewing of the shoe is completed, a latch 416 is fixed to a stud 418 mounted to turn in a bearing in the outer end of the carrier 380, and is arranged to be engaged with the end of a holding catch 420 fixed to a stud 422 mounted to turn in a bearing in the frame of the ma- 130

chine. The catch is held in acting position by means of a coiled spring 424. As the lower end of the carrier 380 is swung to the left upon starting the machine, the acting 5 end of the catch 420 snaps in front of the end of the latch 416 into position to hold the end of the carrier from moving back to the right. When the carrier is thus latched in position, the handle of the arm 414 is released by the operator, and the lever 404 is elevated by the action of the spring 408 to its initial position. When the sewing 10 operation is completed, the latch 416 is automatically thrown out of engagement with the catch 420, allowing the lower end of the carrier to be returned to its right-hand position. Also the latch 416 may be disengaged from the catch 420 to stop the machine at any time that the operator may desire by a 15 manual manipulation of the catch 420 which is provided with a handle for this purpose. As the carrier is released, the spring 384 elevates the slide 382, and through the engagement of the roll 392 with the upper edge 20 of the slot 394, the lower end of the carrier is swung back to the right. By this movement of the carrier the sleeve 334 is depressed. There is a certain amount of lost motion between the sleeve 334 and the collar 340, and the movement of the sleeve caused 25 by the swinging movement of the carrier under the action of the coiled spring 384, is not sufficient to disengage the members of the main driving clutch which are subsequently 30 disengaged at a predetermined point in the rotation of the shaft 22 by mechanism hereinafter described.

The machine is provided with devices 35 which act when the main driving clutch is disengaged to slow down the speed of the sewing cam shaft 22, and to cause the cam shaft to stop in a predetermined position. The mechanism for slowing down and finally stopping the cam shaft 22 of the machine 40 comprises a slow speed friction clutch which is disengaged while the machine is driven through the main driving clutch, and is engaged when the main driving clutch is disengaged. This slow speed clutch when 45 engaged first acts as a friction brake to slow down the speed of the sewing cam shaft to the speed of the driving member of the slow speed clutch, and then as a driving clutch to drive the cam shaft forward to stopping 50 position. The slow speed clutch comprises the driving and driven friction clutch members 426 and 428 mounted on the sewing cam shaft 22. The driving member 426 of the clutch is journaled upon a sleeve 430 secured 55 by means of a washer 432 and a bolt 434 to a reduced portion of the shaft 22 to rotate with the shaft. The clutch member 426 is driven by means of a bevel gear 436 meshing with a bevel gear 438 formed on the 60 clutch member. The gear 436 is mounted up- on the lower end of a sleeve 440 journaled upon a shaft 442 secured at its upper end in the frame. Mounted upon the upper end of the sleeve 440 is a gear 444 which meshes with a gear 446 formed on the disk 318 65 which carries the driving member 320 of the main driving clutch. The gears 438 and 436, and 444 and 446, are so proportioned that the clutch member 426 is rotated at slow speed as compared with the speed of rotation of the driving member of the main driving clutch. The driven clutch member 428 of the slow speed clutch is secured to the sleeve 330 which is mounted upon the shaft 22 to rotate with the shaft, but is movable longitudinally of the shaft to carry the driven member of the clutch into and out of engagement with the driving clutch member. The sleeve is secured to rotate with the shaft by means of a bolt 448 threaded into the sleeve, and engaging in a slot 450 in a flange 452 on the sleeve 430. The clutch members are normally held out of engagement by means of a coiled spring 454 seated at one end in a recess in the flange 452 on 70 the sleeve 430, and at its other end in a recess in the sleeve 330. The movement of the sleeve 330 under the action of the spring is limited by the engagement of the stop nut 456 mounted on the end of the bolt 448 with 75 the flange 452.

The mechanism for controlling the engagement and disengagement of the slow speed clutch comprises a cam groove 458 formed in the sleeve 330, in which engages a cam roll 460 mounted on the upper end of an arm 462 secured to one end of a shaft 464 mounted to turn in a sleeve 466 engaging in a bearing 468 on the frame of the machine. During the sewing operation, or while the 80 main driving clutch of the machine is engaged to drive the machine, the arm 462 is oscillated idly by the cam 458. When the main driving clutch is disengaged, the carrier 380 is locked to the arm 462. To this end the upper end of the slide 382 is formed with a locking projection or bolt 470 which is adapted to engage in a recess 472 formed in a lateral projection 474 on the arm 462 to lock the arm to the lock bolt carrier 380. 85 When the main driving clutch is engaged, the slide 382 is held in lowered position with the locking projection 470 disengaged from the recess 472 by the engagement of the roll 392 with the edge of the slot 394. When the latch 416 is disengaged from the catch 420 the slide 382 is elevated by the action of the coiled spring 384, and as the arm 462 reaches the proper point in its oscillating movements, the locking projection 470 engages in the recess 472 to lock the carrier 380 to the arm. The lower end of the carrier is adapted to be engaged by a spring-pressed plunger 476 mounted to slide in a suitable guideway in the bracket 396. The plunger is attached 90

to one end of a rod 478, and is acted upon by a coiled spring 480 surrounding the rod 478 and interposed between the plunger and one end of the guideway in which the plunger is mounted. The movement of the plunger under the action of the coiled spring 480 is limited by the engagement with the end of the bracket 396 of a stop nut 482 threaded on the end of the rod. When the lock bolt 16 carrier 380 is released the slide 382 rises under the influence of the spring 384 until the locking bolt 470 engages in the recess 472 and the carrier swings on its axis in a direction to carry the lower end thereof to the 20 right until the movement of the carrier is yieldingly limited by the engagement thereof with the plunger 476, the roll 390 then engaging in a recess 484 forming a part of the slot 394. The projection 470 engages in 25 the recess 472 to lock the arm 462 to the carrier 380 when the cam roll 460 is located in the right-hand idle portion of the cam groove 458, as shown in Fig. 6. The continued rotation of the sleeve 330 brings 30 the inclined portion of the cam groove 458 leading from the right-hand idle portion of the groove to the left-hand idle portion thereof into engagement with the roll 460. Through the co-operative action of 35 the cam groove and cam roll during the engagement of the roll in this inclined portion of the cam groove, the sleeve 330 is shifted longitudinally of the shaft 22 to the right (Fig. 5) to engage the members of the slow 40 speed clutch, and the carrier 380 is swung on its axis in a direction to carry the lower end thereof farther to the right from the position shown in Fig. 6. By this movement of the carrier the sleeve 334 is depressed to 45 disengage the members of the main driving clutch. This movement of the carrier occurs against the tension exerted by the spring 480 on the plunger 476, and after the cam roll leaves the inclined portion of the 50 cam groove, and is engaged in the right-hand portion thereof, the members of the slow speed clutch are held in engagement with a pressure depending on the tension of this spring. After the members of the slow 55 speed clutch are engaged, the driving member of the clutch, which is then rotating at slow speed as compared with that of the driven member of the clutch, will first act upon the driven member as a brake to reduce the speed of said member and of the sewing 60 cam shaft upon which it is mounted until these parts are rotating at the speed of the driving member of the clutch. The driving member of the clutch will then act to drive the driven member of the clutch and the sewing cam shaft in a forward direction to stopping position. As the shaft reaches stopping position the members of the slow speed clutch are disengaged, and the rotation 65 of the shaft is arrested by a suitable brake. The sleeve 330 is shifted in the opposite direction, or to the left, (Fig. 5) to disengage the members of the slow speed clutch, when the shaft arrives substantially at the predetermined stopping position 70 through the co-operative action of the cam groove 458 and the cam roll 460, during the engagement of the roll in the inclined portion of the cam groove leading from the left-hand portion to the right-hand portion 75 thereof, and the carrier 380 is at this time swung in a direction to carry the lower end thereof back to the left (Figs. 6 and 15), the swinging movement of the carrier then actuating the devices for engaging the 80 brake. The brake actuating devices (see Figs. 4, 5, 6, 15, 18 and 19) comprise a lever 486 secured to one end of the sleeve 466, and having an arm 488 in which is mounted a pin or stud 490, to the lower end of which is 85 secured an arm 492. The arm 492 is swung toward the forward face of the carrier 380 by means of a spring 494 coiled about the stud 490, and having its upper end secured in a collar 496 fixed to the upper end of the 90 stud, and its lower end secured in the arm 488. The acting or right-hand end of the arm 492 is adapted to engage the left side of a projection 498 on a pin 500 projecting forwardly from the slide 382. During the sewing operation, or while the main driving clutch is engaged, the lower end of the carrier 380 is held in the position shown in Fig. 15, through the engagement of the latch 416 with the catch 420, so that the lower 100 end of the slide 382 and the pin 500 occupy substantially the positions shown in Figs. 15, 18 and 19, the slide being held in depressed position by the engagement of the roll 392 with the edge of the slot 394. The pin 500 105 is located on the slide so that it then lies below the arm 492. As the latch 416 is released from the catch 420 at the end of the sewing operation, and the slide 382 rises under the influence of the coiled spring 384, the lower end of the carrier 380 does not swing to the right sufficiently to enable the end of the arm 492 to swing toward the carrier into position to engage the left side of the projection 498 on the pin 500, but the 110 end of the pin engages an inclined face 502 formed on the rear side of the end of the arm, and moves the arm forwardly away from the carrier. As the lower end of the carrier is swung to the right immediately 115 after the engagement of the members of the slow speed clutch through the action of the cam groove 458 on the cam roll 460, the movement of the carrier carries the projection 498 beyond the end of the arm 492 and the arm is then swung rearwardly into position to engage the left side of the projection. As the lower end of the carrier 380 is swung 120 back to the left the lever 486 will be swung to the left through the engagement of the 125 130

projection 498 with the end of the arm 492. This movement of the lever effects the setting of the brake. The central portion or hub of the arm 492 is provided with an abutment face 504 for engagement with an arm 503 carried by a brake actuating ring 508 surrounding the sewing cam shaft 22. The ring is pivoted upon an eccentric pin 510, and is formed with oppositely projecting lugs 512 which engage in recesses 514 in a brake disk 516 carried by a sleeve 518 mounted on the sewing cam shaft to slide longitudinally of the shaft but held from rotation with the shaft. The brake disk and the sleeve are held from rotation with the sewing cam shaft by the engagement of the lugs 512 on the ring 508 in the recesses 514 in the brake disk. The lugs 512 are formed with curved abutment faces 520 for engagement with the inner faces 522 of the recesses in the brake disk. The brake disk 516 is provided with a facing of friction material 524 for engagement with a brake surface 526 formed on the cam disk 48. The sleeve 518 is normally held in position on the shaft 22 to maintain the brake disk 516 out of engagement with the brake surface 526 of the cam disk 48, by means of an annular leaf spring 528 interposed between one end of the bearing 530 and a ring or collar 532 threaded upon the end of the sleeve. As the lever 486 is swung to the left at the time of the disengagement of the slow speed clutch in the manner above described, the abutment face 504 on the arm 92 engages the arm 506 on the brake actuating ring 508, and turns said ring about the eccentric pin 510 upon which it is pivoted, thereby causing the ring to move the brake disk 516 into engagement with the brake surface 526 of the cam disk 48 to arrest the rotation of the sewing cam shaft. By the adjustment of the eccentric pin 510 upon which the brake actuating ring is pivoted, the position of said ring may be regulated so as to produce the required action between the members of the brake to stop the rotation of the sewing cam shaft quickly and efficiently at the predetermined point in the rotation of the shaft. The mechanism for disengaging the latch 416 from the catch 420 upon the completion of the sewing of the shoe will now be described (see Figs. 4, 9, 20, 21, 22 and 23). The latch 416 is formed with an arm 534 having at its end a socket 536 which is adapted to receive the spherical end 538 of a rod 540 mounted in a hollow cylinder 542. Surrounding the rod 540 within the cylinder 542 is a coiled spring 544 interposed between the end wall of the cylinder and a shoulder 546 on the rod. The movement of the rod 540 under the influence of the coiled spring 544 is limited by the engagement of a washer 548 held by a nut 550 threaded on the outer end of the rod with the end of the cylinder 542. Pivotedly connected with the cylinder 542, by means of a pin 552, is a block 554 formed with an upwardly projecting stud 556 by which the block is pivotally connected with the outer end of an arm 558 pivoted to turn loosely on a rock shaft 560 mounted in a bearing in the frame of the machine. An arm 562 is fixed to the upper end of the rock shaft 560 and is adapted to engage a boss 564 on the arm 558. To the lower end of the rock shaft 560 is secured an arm 566, the outer end of which is pivotally connected at 568 with one end of a link 570. The other end of the link 570 is pivotally connected at 572 with one end of a link 574, the other end of which is pivotally connected at 576 with the outer end of an arm 578, secured to the rock shaft 580, mounted in a bearing 582 in the frame. To the lower end of the rock shaft 580 are secured two actuating arms 584 and 586. The arm 584 is arranged above the arm 586 and carries a cam roll 588 for engagement with a cam rise 590 formed on the upper half of the periphery of a cam disk 222 secured to the pattern cam shaft, and the arm 586 carries a cam roll 592 for engagement with another cam rise 594 formed on the lower half of the periphery of the cam disk 222. The position of the pivotally connected links 570 and 574 is controlled by means of a link 596 pivotally connected at one end with the link 574, and at its other end with an arm 598 on the lever 262, which is actuated by the operator in changing from a right shoe to a left, or from a left to a right to reverse the direction of rotation of the pattern cam shaft. When a right shoe is being sewn, the arm 598, the link 596, and the pivotally connected links 574 and 570 controlled thereby are located substantially in the positions shown in Figs. 9, 21 and 23. With the parts adjusted as shown in these figures, the latch 416 is disengaged from the catch 420 by the movement of the arm 586 produced by the action of the peripheral cam rise 594 on the cam disk 222 on the cam roll 592. Fig. 23 shows the positions of the parts after the actuation of the arm 586 by the cam rise 594. By the action of this rise on the cam roll 592, the arm 586 is swung forwardly, and the arm 578 is swung to the right. By this movement of the arm 578 through the links 574 and 570, the arm 566 attached to the lower end of the rock shaft 560, and the arm 562 attached to the upper end of said rock shaft, are swung forwardly. During the forward swinging movement of the arm 562, said arm engages the boss 564 on the arm 558 and swings the latter arm forwardly, and through the connection between the arm 558 and the latch 416, the latch 416 is actuated to disengage its acting end from the catch 420. When a left shoe is being

sewn, the arm 598, link 596, and pivotally connected links 574 and 570 are located in the positions shown in Figs. 22 and 24. With these parts adjusted as shown in these figures, the latch 416 is disengaged from the catch 420 by the movement of the arm 584 produced by the action of the peripheral cam rise 590 on the cam disk 222 on the cam roll 588. By the action of this cam rise on the cam roll 588, the arm 584 is swung forwardly, and the arm 578 is swung to the left. Fig. 21 shows the positions of the parts after the actuation of the arm 584 by the cam rise 590. The movement of the arm 578 to the left through the links 574 and 570 on account of the positions of these links will swing the arm 566 and the arm 562 forwardly as before, to actuate the arm 558, to disengage the acting end of the latch on the catch. The shifting of the links 570 and 574 from one position to the other in changing from a right to a left shoe, or from a left shoe to a right, is produced by the movement of the arm 598 when the lever 262 is actuated to reverse the direction of rotation of the correcting cam shaft.

Through the mechanism described, the machine is stopped at the predetermined point in the sewing of the seam chosen for the completion of the seam. This point is obviously determined by the position of the rise 594 on the cam disk 222 when a right shoe is being sewn, or by the position of the rise 590 on the cam disk when a left shoe is being sewn.

When the sewing operation is completed, and the action of the machine is thus arrested, the operator unjacks the shoe, severs the needle and shuttle threads, and removes the shoe from the machine. Before another shoe can be sewn on the machine, the jack, which during the sewing operation has been turned upon its axis substantially half a revolution, and lies with its toe rest to the left of the sewing point, must be turned to its initial starting position. This is done by throwing into action a driving mechanism which drives the pattern cam shaft independently of the sewing cam shaft until the pattern cam shaft has described substantially a complete revolution from the point at which it started at the beginning of the sewing of the seam. In the construction shown (see Figs. 4, 5 and 9) this mechanism comprises a roll clutch, the driving member of which, indicated at 600, is keyed to a reduced portion of the shaft 316, as is shown clearly in Fig. 4. This member is formed with a circular flange 602 within which projects the upper end of the driven member 604 of the clutch. The driven member of the clutch consists of a sleeve journaled upon a bushing 606 fixed to the reduced lower end of the shaft 316. The driven member of the clutch is formed at its upper end with a series of flat faces indicated at 608, between which and the inner face of the flange 602 on the driving member of the clutch are located a series of clutch rolls 610. The position of the clutch rolls 610 relative to the flat faces 608 on the driven member of the clutch is controlled by a clutch controlling sleeve 612 mounted to turn upon the exterior of the driven member of the clutch, and having a series of spaced projections 614 between which the clutch rolls 610 are placed. The clutch controlling sleeve 612 is acted upon by a coiled spring 616, attached at one end to a pin 618 mounted in the driven clutch member, and at the other to a pin 620 mounted in the clutch controlling sleeve 612. This spring tends to turn the clutch controlling sleeve in a right hand direction (Figs. 5 and 9) relative to the driven member of the clutch to cause the clutch rolls 610 to wedge between the flat faces 608 on the driven clutch member and the inner surface of the flange 602 on the driving member of the clutch to clutch the driven member to the driving member. When the clutch controlling sleeve is free to turn under the action of the spring, it will cause the engagement of the clutch. The devices for controlling the position of the clutch controlling sleeve 612 relative to the driven member of the clutch comprises a lever 622 pivoted at 624 upon a ring 626 mounted upon the exteriors of the clutch controlling member and of the driven member of the clutch. The ring 626 has a projection 628 formed thereon, which is engaged on one side by a plunger 630 mounted in a suitable bore in the frame, and actuated by a spring 632, and on the other by a set screw 634 threaded into the frame. The ring is thus held in position on the clutch, but is permitted to yield slightly in one direction. The lever 622 is formed with a cam-shaped inner end adapted to engage the exterior of the clutch controlling sleeve 612, as shown in Fig. 9, to hold said sleeve from turning movement. In throwing the clutch into operation, the lever 622 is swung about its connection with the ring 626 to disengage its inner end from the exterior of the sleeve 612, allowing the latter sleeve to turn relatively to the driven member of the clutch under the action of the coiled spring 616. The clutch will thus be engaged, and the member 604 of the clutch will be driven in the direction indicated by the arrows in Figs. 5 and 9, by the driving member 600 of the clutch. To cause the disengagement of the clutch, the lever 622 is swung in the opposite direction about its connection with the ring 626 to re-engage the cam-shaped inner end of the lever with the exterior of the clutch-controlling sleeve. The engagement of the inner end of the lever 622 with the sleeve 612 will arrest the rotation of the clutch controlling sleeve, while the rotation of the driven member of

the clutch will continue until the rolls 610 are released from wedging engagement between the flat faces 608 on the driven member 604 of the clutch and the inner face of 5 the flange 602 on the driving member 600, thus causing the disengagement of the clutch. This rotary movement of the driven member of the clutch while the clutch controlling sleeve 612 is held from rotation, 10 stretches the spring 616, and in order to prevent the driven member of the clutch from turning backwardly under the influence of the spring after its rotation in a forward direction ceases, a recoil dog is provided. 15 This dog consists of a ball 636 mounted in an inclined bore 638 in the ring 626 leading to the outer surface of the driven clutch member. The inclination of the bore 638 relative to the outer surface of the driven 20 clutch member is such that when the ball is located in the forward end of the bore it will bind between the outer face of the bore and the outer surface of the driven clutch member. The ball is acted upon by a coiled 25 spring 640 interposed between the ball and a screw 642 threaded into the outer end of the bore, which spring tends to force the ball into the forward end of the bore or into clutching engagement with the outer surface 30 of the driven clutch member. This arrangement of the recoil dog will thus prevent any reverse rotation of the driven clutch member under the action of the spring 616. The lower end of the driven member 604 of the 35 roll clutch is formed with a series of inclined clutch teeth 644 facing in the direction of rotation of the clutch. The clutch teeth are adapted to be engaged by one end of a clutch pawl 646 arranged diametrically of the 40 clutch member 604, and having a spherical bearing end 648 having a bearing in a bore 650 in a flange 652 formed on the upper end of the shaft 254. The pawl 646 is engaged by the upper end of a pin 654 mounted in a 45 bore in the shaft 254, and acted upon by a coiled spring 656 which tends to hold the acting end of the pawl in engagement with the ratchet teeth 644. To the lower end of the shaft 254 is secured the bevel gear 252 50 which forms the driving connection between the gears 248 and 250, as hereinbefore described. During the sewing operation, the roll clutch then being disengaged, the end of the pawl 646 passes idly over the teeth on the lower end of the clutch member 604, as 55 the gear 252 and the shaft 254 to which it is secured are rotated. After the machine has been stopped at the completion of the sewing operation, and the shoe has 60 been removed from the jack, the operator throws the roll clutch into operation. The member 604 of the clutch is then driven in the direction of the arrow, (Figs. 5 and 9), and through the engagement of the 65 end of the pawl 646 with the teeth 644 on

the lower end of the clutch member 604, the shaft 254 and the gear 252 are driven in the same direction as they are driven during the sewing operation, but at a very much higher speed, since they are clutched directly 70 to the counter shaft 316. The pattern cam shaft, through the operative connections between said gear 252 and the shaft, will be driven at a relatively high speed in the same direction as during the sewing operation, 75 until the jack is located again in its initial or starting position. When the jack has been returned to its initial position, the roll clutch is automatically disengaged to arrest the rotation of the pattern cam shaft. 80

The lever 622 is actuated and controlled to cause the engagement and disengagement of the roll clutch as above described by the following mechanism. Pivotedly connected at 658 to the outer end of the lever 622, and arranged to operate in a guide 660, Fig. 15, is an arm 662, the forward end of which is adapted to engage the rear side of an arm 664 fixed to a stud 666 mounted to turn in a bearing in the frame of the machine. 85 With the forward end of the arm 662 engaged with the arm 664, the lever 622 is held in position with the inner cam shaped end of the lever engaged with the flange 668 on the sleeve 612. To the stud 666 which carries the arm 664 is secured an operating handle 670, by which the arm 664 may be turned to disengage it from the end of the arm 662. The arm 664 is yieldingly held in 90 position in front of the end of the arm 662 by means of a coiled spring 672. The arm 662 is formed with a projection 674 which is engaged by the forward end of a plunger 676 mounted in a suitable bore in the frame of the machine, and acted upon by a coiled 95 spring 678. To throw the roll clutch into operation, the operator turns the operating handle 670 to swing the arm 664 out of engagement with the end of the arm 662. 100 After the arm 662 is thus released it is moved forwardly by the action of the plunger 676, and the lever 622 is swung forwardly about its pivotal connection with the ring 626 to disengage its inner end from the flange on the sleeve 612. This causes 105 the roll clutch to be thrown into operation in the manner previously described. In order to actuate the lever 622 to engage its inner end with the flange on the clutch controlling sleeve 612, and thus throw the roll clutch out of operation when the cam shaft has been turned to starting position, the arm 562 fixed to the upper end of the shaft 560 is arranged to engage a shoulder 110 680 formed on the arm 662. As the pattern cam shaft arrives at its initial or starting position, the arm 562 is swung rearwardly, and through its engagement with the shoulder 680 it actuates the arm 662 and the lever 622 to cause the inner end of the lever 115 120 125 130

to engage the flange on the clutch controlling sleeve 612 to throw the roll clutch out of operation. With the parts adjusted for sewing a right shoe, as shown in Figs. 9, 21, 5 and 23, this movement of the arm 584 is produced by the engagement of the rise 590 on the periphery of the cam disk 222 upon the cam roll 588 carried by the arm 584. With the parts adjusted as shown in 10 these figures, the forward movement of the arm 584 produced by the action of the cam rise 590 on the roll 588, through the connections described between the arm 584 and the arm 566, swings the latter arm rearwardly and turns the rock shaft 560 to swing the arm 562 rearwardly to throw out the roll clutch. Fig. 20 shows the positions of 15 certain of the parts after the actuation of the arm 584 by the cam rise 590. With the parts adjusted for sewing a left shoe, as shown in Figs. 22 and 24, this movement of the arm 562 is produced by the action of the cam rise 594 on the periphery of the cam disk 222 upon the cam roll 592 carried by the arm 586. With the parts adjusted as 20 shown in these figures, the forward movement of the arm 586 produced by the action of the rise 594 on the roll 592 swings the arm 566 rearwardly and turns the rock shaft 560 to swing the arm 562 rearwardly to throw out the roll clutch. Fig. 22 shows the positions of certain of the parts after 25 the actuation of the arm 586 by the cam rise 594. As the arm 662 is moved rearwardly by the action of the arm 562 thereon, the latch-arm 664 is swung in front of the forward end of the arm 662 to retain said arm and the lever 622 in position.

When sewing along the shank of a shoe, 40 the shoe is tilted about an axis substantially parallel with, or extending in the general direction of the longitudinal axis of the shoe bottom to an extent such that the plane of the portion of the projecting edge of the sole at the point of operation does not lie parallel with the work engaging faces of the presser foot and work support. The result of this tilting of the shoe, when operating along the shank, is that the presser foot and work support do not correctly measure the thickness of the work, but the presser foot is separated from the work support by a distance greater than the thickness of the work. If this error in the work 45 measuring operation of the work support and presser foot were uncorrected, or if the throw of the pull-off, when operating along the shank, were determined in the usual manner by the distance between the presser foot and work support, the pull-off would draw off from the supply during each cycle of operations a length of thread in excess of that required for the formation of the succeeding stitch, and this would result in a looseness in 50 the stitches. To correct or compensate for

this error in the work measuring action of the work support and presser foot, the present machine is provided with mechanism for diminishing the throw of the pull-off from that determined by the relative positions of the presser foot and work support when operating along the shank of the shoe. In the construction shown (see Figs. 1, 7, 9 and 13) the cam lever for actuating the oscillating lever 70 of the pull-off mechanism is indicated at 682. The cam lever is pivoted upon the shaft 684, and is provided with an arm 686 carrying a cam roll 688 engaging in a cam groove in the cam disk 48. The cam lever is provided with a second arm 690 upon which is pivoted at 692 a bell crank 694, one arm of which is connected by a link 696 with the oscillating lever 70. The other arm of the bell crank 694 is connected by a link 698 with an arm 700 fixed to a rock shaft 702, mounted at one end in a bearing in a bracket 704 on the frame, and at the other end in a bearing in an arm 706 formed on the bracket 708 secured to the frame.

The parts are shown in Fig. 7 of the drawing substantially in the positions which they assume during each cycle of operations when the pull-off is at the beginning of its acting stroke except that the presser foot is lifted, the lifting of the presser foot having caused the pull-off to assume a position somewhat below its normal starting position. When operating along the shank of a shoe the rock shaft 702 is adjusted so as to locate the arm 700 substantially in the position shown in Fig. 7. With this adjustment of the rock shaft the full throw is not imparted to the pull-off as determined by the position of the presser foot, but its throw has been diminished by the adjustment of the arm 700 to 55 compensate for the error in the work measuring function of the work support and presser foot when operating along the shank. In passing from the shank to the forepart of the shoe the rock shaft 702 is turned in a direction to swing the arm 700 toward the front of the machine. As will be obvious from an inspection of Fig. 7, this adjustment of the arm 700 through the link 698, the bell crank 694, the link 696 and the lever 70 will 60 adjust the pull-off lever, consisting of arm 64, rock shaft 62 and arm 60, so that the pull-off roll 14 will start from a lower position at the beginning of the acting stroke of the pull-off lever. The parts are constructed and arranged so that at the end of the acting stroke of the pull-off lever the link 698 is 65 swung substantially into line with the arm 700. This adjustment of the arm 700, therefore, will produce substantially no variation 70 in the position of the pull-off at the end of its acting stroke. Since the limit of the acting stroke of the pull-off is substantially the same with either position of the arm 700, the 75 length of the acting stroke of the pull-off 80

will be increased by the adjustment of the arm, as described. In passing from the forepart of the shoe to the shank upon the opposite side of the shoe the rock shaft 702 is 5 turned to swing the arm 700 rearwardly to its initial position. This adjustment of the arm will again reduce the stroke of the pull-off for the sewing of the stitches along the shank. The mechanism provided for effecting 10 the adjustment of the rock shaft 702 in timed relation to the movements of the shoe in the manner described is operated from the pattern cam shaft 178. In the construction shown a bevel gear 710 is mounted on 15 the rock shaft 702 and meshes with the bevel gear 712 mounted upon the upper end of a shaft 714 having a bearing at its upper end in an arm 716 on the bracket 708 and at its lower end in an arm 718 on the bracket 720. 20 To the lower end of the shaft 714 is attached an arm 722, carrying at its end a cam roll 724, arranged to engage a peripheral cam on the cam disk 726, mounted on the pattern cam shaft 178. In order to maintain the 25 cam roll in engagement with the periphery of the cam disk 726, a spring 728 is coiled about the shaft 714 and has the end of one arm engaged with the arm 722, and the end of its other arm engaged behind the 30 bracket 720.

The machine is provided with an edge gage 730, movably mounted above the upper surface of the work support 18 to engage the edge of the sole. The edge gage is automatically actuated to advance the edge gage into predetermined operating position in engagement with the sole edge and to retract the same out of operating position at predetermined points in the sewing operation 35 or in timed relation to the passage of the shoe through the machine. The edge gage is retracted from engagement with the edge of the sole of the shoe when sewing along the shank. The distance of the line of 40 stitches from the edge of the sole is then determined by the engagement of the forward edge of the work support with the upper, and the line of stitches is formed relatively remote from the sole edge or close to the upper. When passing from the shank to the forepart of the shoe, the edge gage is moved forward into engagement with the sole edge so as to cause the line of stitches to be formed relatively close to the sole edge 45 or relatively remote from the upper as compared with the stitches along the shank. When passing from the forepart to the shank, the edge gage is withdrawn from engagement with the sole edge. In connection 50 with the edge gage mechanism, automatically operating feed changing mechanism is employed, which acts to shorten the length of stitch in passing from the shank to the forepart of the shoe, and to increase the 55 length of stitch in passing from the forepart to the shank. In the construction shown, (see Figs. 1, 2, 9, 11 and 12) the edge gage 730 is mounted upon the upper end of a shaft 732, journaled in bearings in the upright 28 60 on the feed slide 30. This manner of mounting the edge gage 730 enables the edge gage to swing over the upper surface of the work support into and out of acting position. Upon the lower end of the shaft 732 is formed a series of spiral gear teeth meshing 65 with the teeth of the spiral gear 734, fixed to one end of a shaft 736, journaled in bearings in the dove-tailed portion of the feed slide. Upon the other end of the shaft 736 is secured a disk 738, upon which is formed 70 a series of gear teeth 740, meshing with the teeth of the gear segment 742 carried by the upper end of an arm 744, fixed to one end of the shaft 746, mounted in bearings in a bracket 748, secured to the frame of 75 the machine. On the other end of the shaft 746 is secured an arm 750, carrying at its outer end a roll 752, engaged by an arm 754, fixed to the upper end of a rock shaft 756. A second arm 758 is fixed to the shaft 756 80 and carries at its outer end a cam roll 760, arranged to engage a peripheral cam on the cam disk 182. The arm 744 is acted upon by a coiled spring 762, attached at one end of the arm, and at the other to a point 85 on the frame of the machine, which spring tends to swing the arm toward the rear of the machine, and thus to hold the edge gage in retracted position and also to maintain the cam roll 760 in engagement with 90 the periphery of the cam disk 182. Through the action of the peripheral cam on the cam disk 182 on the cam roll 760, and the action of the spring 762 on the arm 744, the said 95 arm is swung in opposite directions in timed 100 relation to the other parts of the machine to advance the edge gage into operating position in passing from the shank of the shoe to the forepart, and to retract the edge gage from operating position in passing 105 from the forepart to the shank. In passing from the shank of the shoe to the forepart the arm 744 is swung forwardly and through the disk 738, the shaft 736 and the shaft 732 this movement of the arm swings the edge 110 gage 730 forwardly into operative position. In a corresponding manner, in passing from the forepart to the shank of the shoe the arm 744 is swung rearwardly, thereby 115 through the connections described swinging the edge gage 730 rearwardly out of operating position. When starting a seam along the shank of the shoe, the lever 36, the angular position of which determines the length 120 of the stitch, rests against the rear side of a pin 54, placed in one of the perforations in the gage plate 50, the position of this pin determining the length of the stitches to be 125 formed along the shank. The rearward movement of the lever is limited by means 130

of a pin placed in one of the perforations in the gage plate 50 to the rear of the lever. In sewing about the forepart of the shoe the lever 36 is adjusted so that it engages the forward side of the rear pin, the position of which determines the length of the stitches formed about the forepart. When sewing along the shank on the side of the shoe last sewn the lever 36 is again adjusted so that it engages the rear side of the front pin 54. In the present machine the feed regulating lever 36 is automatically swung from its forward position to its rearward position in passing from the shank to the forepart of the shoe, and is swung back to its forward position in passing from the forepart to the shank through connections with the edge gage mechanism. In the construction shown, a plate 764 is adjustably secured to the lever by means of a screw 766 passing through a slot 768 in the plate and threaded into the lever. The forward end of the plate is formed with a down-turned projection 770 adapted to be engaged upon its rear side by a shoulder 772 formed on the disk 738. Secured upon the outer end of the shaft and preferably formed integral with the disk 738 is a block 774, upon which is adjustably mounted a segmental plate 776, secured to the block by means of a screw 778, passing through a slot 780 in the plate and threaded into the block. The upper or forward end of the segmental plate 776 is adapted to engage the forward side of the projection 770 on the plate 764. When the seam is started along the shank of the shoe, the shoulder 772 on the disk 738 is engaged with the rear side of the projection 770 on the plate 764. In passing from the shank of the shoe to the forepart, the disk 738 is turned in a right hand or clockwise direction (Fig. 12) by the action of the arm 744, to advance the edge gage 730 into operating position. During this movement of the disk 738, the end of the segmental plate 776 engages the forward side of the projection 770 on the plate 764 and moves the latter plate and the lever 36 to which it is attached, toward the rear of the machine until the lever brings up against the forward side of the rear pin 54. The lever 36 is thus positioned to shorten the stitch length for sewing about the forepart of the shoe. In passing from the forepart of the shoe to the shank upon the opposite side of the shoe, the disk 738 is turned in a left-hand or counter-clockwise direction, Fig. 12, by the action of the arm 744, to retract the edge gage from operating position. During this movement of the disk the shoulder 772 is engaged with the rear side of the projection 770 on the plate 764 and moves said plate and the lever 36 forwardly until the lever engages the rear side of the front pin 54, thus restoring the lever to its initial position for sewing along the shank of the shoe. The provision for adjustment of the plate 764 on the lever 36 and of the segmental plate 776 on the block 774 enables the action of the feed changing mechanism to be regulated to compensate for variations in the limiting positions of the lever 36, as determined by the pins 54. These pins, of course, may be placed in different perforations in the gage plate 50 to give any desired length of stitch along the shank, or about the forepart of the shoe.

The mounting of the edge gage on the feed slide, so that it moves with the awl during the feed, is of considerable advantage. In machines employing an edge gage which is fixed in the direction of feed, the awl is often thrown out of line with the needle during the feeding of the work so that the needle, as it advances through the work, does not enter the perforation made in the work by the awl. This difficulty is due chiefly to the leading on of the work by the operator, or to the crowding of the work in advance of the point of operation to the rear to ensure the positioning of the edge of the sole firmly against the edge gage. This crowding of the work rearwardly in advance of the point of operation often causes the edge of the sole in advance of the point of operation to lie in a direction oblique to the line of feed, extending from the point of operation toward the rear of the machine. When this inclined edge of the work engages a fixed edge gage during the advancing movement of the feed slide, through the action of the edge gage upon the edge of the work, the point in the work engaged by the awl is crowded forwardly, thereby throwing the awl out of line with the needle. This difficulty is obviously corrected by mounting the edge gage upon the feed slide so that it moves with the awl.

The tension mechanism of the machine (see Fig. 17) comprises a tension wheel about which the thread passes on its way from the supply to the sewing point, and devices to control the rotation of the tension wheel to place the thread under a substantially constant tension during the sewing operation, and to relieve the thread of tension when the machine is stopped at the completion of a seam so that the thread may be drawn freely from the supply as the shoe is removed from the machine. These devices comprise a lever 782 (see Fig. 17), secured to one end of a rock shaft 784, and a link 786 connecting the upper end of the lever with an arm on the lever 370. As the machine is stopped at the end of the sewing operation, the movement of the carrier 380 swings the lever 782 substantially into the position shown in Fig. 17. The rock shaft 784 acts on the tension wheel through connections hereinafter described. The tension wheel consists of two

sheet metal disks 788 placed side by side and having oppositely bent interengaging peripheral projections for engaging the thread. These disks are clamped between the disks 790 fixed upon a sleeve 792 journaled upon an enlargement 794 formed on a shaft 796 secured at one end in the machine frame. The disks 790 are recessed to receive the friction washers 798. The friction washers 10 are engaged by friction disks 800 and 802 mounted on the shaft 796, and held from rotation on the shaft by means of a pin 804 passing through the enlargement 794 and having its ends engaged in the disks. The 15 friction disk 802 is formed upon one end of a sleeve 806, upon which is mounted a collar 808 having a threaded engagement with the sleeve and a second sleeve 810 free to slide longitudinally of the sleeve 806. Interposed between a flange on the collar 808 and a flange on the sleeve 810 is a coiled spring 812. The movement of the sleeve 810 on the sleeve 806 is limited by the engagement of a ring 814 embedded in a groove in 20 the sleeve 806, with a shoulder on the sleeve. The outer end of the sleeve 810 is engaged by a flange 816 on a sleeve 818 mounted to slide on the end of the shaft 796. A rod 820 is slidably engaged at one end in the outer 25 end of the bore in the sleeve 818 and at its opposite end is threaded into a block 822, pivoted by means of a stud 824 to an arm 826 secured to the forward end of a rock shaft 784. The rod 820 is formed with an enlargement 30 830 arranged to engage the outer end of the sleeve 818. Interposed between a collar 832 on the rod 820 and the flange 816 on the sleeve 818 is a coiled spring 834, the strength of which is very slight as compared 35 with that of the coiled spring 812. The parts are shown in the drawings in the positions which they assume when the tension is released. It will be noted that the enlargement 40 830 is disengaged from the outer end of the sleeve 818, and that the shoulder 836 on the sleeve 810 rests against the ring 814. The coiled spring 812 is, therefore, inactive and the friction disks 800 and 802 are held together or are engaged with the friction washers 798 only by the force of the spring 834. This spring is preferably so light that the force exerted thereby is only sufficient to hold the parts in position, so that the friction disks 800 and 802 furnish very little 50 frictional resistance to the turning of the tension wheel. When the lever 782 is swung upon its axis upon starting the machine, the light spring 834 is first compressed and the enlargement 830 is engaged with the end of 55 the sleeve 818, after which the sleeve 818 and the sleeve 810 engaged thereby are moved longitudinally of the shaft 796. This movement of the sleeve 810 compresses the coiled spring 812 which, acting on the sleeve 60 806, tends to force the friction disk 802 to-

ward the friction disk 800. Thus during the sewing operation the rotation of the tension wheel is resisted by the frictional action of the friction disks 800 and 802 on the friction washers 798, produced by the action of the 70 coiled spring 812. The force exerted by the coiled spring 812 may be regulated by adjusting the collar 808 on the sleeve 806. When the lever 782 is swung back to the position shown in the drawings upon the stopping of the machine at the completion of the 75 sewing of a seam, the spring 812 moves the sleeve 810 outwardly on the sleeve 806 until the shoulder 836 on the sleeve 810 engages the ring 814, rendering the coiled spring 812 inactive, after which the enlargement 830 is disengaged from the end of the sleeve 818.

The present machine is also provided with a mechanism for automatically unlocking and lifting the presser foot upon stopping the machine at the completion of the seam, so that the work may be readily removed from the machine (see Figs. 4, 6, 7, 8, 18 and 19). The machine is stopped at a point in a cycle of operations when the needle and awl are both retracted out of engagement with the work, and the thread is released or unlocked by the thread locking device so that it can be drawn freely from the supply. At this point in a cycle the presser foot is locked in work engaging position by the engagement of the pawls 98 and 112 with the teeth on the rear end of the arm 86 and on the rear end of the presser foot lever. The pawls 98 and 112 are disengaged from the teeth on the rear end of the arm 86 and on the rear end of the presser foot lever to unlock the presser foot to permit the presser foot to be lifted by means of a pawl disengaging lever 838 pivoted upon the stud 80 and provided with rearwardly extending projections 840 and 842 adapted to engage pins 844 and 846 mounted respectively on the pawls 98 and 112. The projections 840 and 842 are formed respectively with inclined faces 848 and 850 for engaging the pins to throw out the pawls during the pawl disengaging movement of the lever 838, and with stop faces 852 and 854 for engaging the pins to limit the movement of the lever. The lever 838 is provided with an operating arm 856, and a lifting arm 858 is rigidly mounted upon the presser foot lever immediately in front of the arm 856. A lever 860 is pivoted upon a stud 862 upon the arm 856 of the pawl disengaging or unlocking lever 838, and is formed with a forwardly extending curved arm 864, the rear side of the forward end of which is arranged to engage a pin 866 mounted upon the lifting arm 858 secured to the presser foot lever. The lever 860 is formed with a downwardly extending arm 868, connected by a link 870 with an arm 872 fixed to one end of the rock shaft 874.

To the opposite end of the rock shaft is secured an arm 876 having at its outer end a socket to receive one end of a ball-ended link 878. The other end of the link is received in a socket in the arm 880 on the lever 486. As the lever 486 is swung to the left, Figs. 6 and 19, by the action of the carrier 380 upon the stopping of the machine, through the connection of said lever with the rock shaft 874, the rock shaft is turned in a direction to swing the arm 872 forwardly. During the first part of the forward swinging movement of the arm 872, the arm 856 of the unlocking lever 838 is swung forwardly by the forward thrust of the link 870, the swinging of the lever 860 upon the stud 862 being limited by the engagement of the arm 864 of the lever with the pin 866. The unlocking lever is thus actuated to disengage the pawls 98 and 112 from the teeth on the rear ends of the arm 86 and of the presser foot lever. When the movement of the unlocking lever is stopped by the engagement of the faces 852 and 854 formed on the projections 840 and 842 on the lever with the pins 844 and 846, the lever 860 is swung about the stud 862, and through the engagement of the curved upper side of the arm 864 with the pin 866 the presser foot is lifted from the work.

The present machine is also provided with mechanism for stopping the machine automatically when the needle thread breaks. In the present construction (see Figs. 7 and 9) the auxiliary take-up arm or lever 56 is formed with a downwardly extending arm 882 upon which is mounted a laterally extending pin 884 passing through a slot 886 in the frame of the machine. The pin 884 is arranged to be engaged by the forwardly facing end of one arm of a lever 888, pivoted on the stud 890. Upon the other arm of the lever 888 is mounted a pin 892 adapted to be engaged by the end of an arm 894 secured to a forwardly extending arm on the feed slide actuating lever 42. During the stitch setting stroke of the take-up, the auxiliary take-up 56 is swung downwardly by the pull on the thread, and the pin 884 engages the lever 888 and swings the lever substantially into the position shown in Fig. 9. As the lever 42 is actuated to advance the feed slide, the end of the arm 894 engages the pin 892 and swings the lever 888 in the opposite direction into position to be again engaged by the pin 884. In order to hold the lever 888 either in the position in which it is placed by the action of the pin 884 thereon, or in the position in which it is placed by the action of the arm 894 on the pin 892, a retaining pin 896, actuated by a spring 898, is mounted in the frame of the machine beneath the lever 888, and is provided with a pointed upper end adapted to engage in either of the recesses 900 and 902 formed

in the lever. The arm 894 is formed with a projection 904 arranged to engage a shoulder 906 upon an arm 908 pivoted at 910 to the outer end of an arm 912 loosely pivoted on the shaft 560, and having its hub secured to and preferably integral with the hub of the arm 558. The arm 908 is acted upon by a coiled spring 914 attached at one end to a pin 916 secured in the arm, and at the other to the frame of the machine, which tends to swing the arm 908 about its pivotal connection with the arm 912 in a direction to carry the shoulder 906 in front of the projection 904. Upon the end of the arm 908 is mounted a pin 918 adapted to engage the lever 888 to limit the movement of the arm 908 under the action of the coiled spring 914. The parts are so constructed and arranged that with the lever 888 in the position shown in Fig. 9, the arm 908 is prevented from swinging rearwardly far enough to carry the shoulder 906 into position to be engaged by the forward side of the projection 904 by the engagement of the end of the pin 918 with the lever.

The parts are shown in Fig. 9 in the position which they assume at a point in a cycle of operations just before the feed slide has completed its retracting stroke. It will be noted that the projection 904 has not cleared the shoulder 906, and that the arm 908 is held out of contact with the end of the projection by the engagement of the end of the pin 918 with the lever 888. Starting with the parts in the positions shown in this figure, the parts have the following mode of operation during each cycle while the needle thread is unbroken. As the forward arm of the lever 42 swings to the right to complete the retracting stroke of the feed slide, the projection 904 clears the shoulder 906. During this movement of the lever 42, and as the forward arm of the lever swings to the left to advance the feed slide, the lever 888 remains in the position shown in this figure, and through its engagement with the end of the pin 918, prevents the arm 908 from being swung rearwardly to carry the shoulder 906 in front of the forward side of the projection 904. After the forward side of the projection has passed the shoulder, the arm 894 engages the pin 892 and swings the lever 888 into position to be engaged by the pin 884. The arm 908 then rests against the end of the projection 904. As the forward arm of the lever 42 swings back to the right, the lever 888 is swung back into the position shown in Fig. 9 by the action of the auxiliary take-up before the projection 904 clears the shoulder 906. In case the needle thread is broken at any point in the sewing of the seam, during the next succeeding stroke of the take-up the lever 888 is not engaged and moved by the pin 884, but is held by the retaining pin 896 in

the position into which it is moved by the action of the arm 894 on the pin 892. With the lever 888 in this position, when the forward arm of the lever 42 swings to the right, 5 after the projection 904 clears the shoulder 906, the arm 908 is swung rearwardly by the spring 914, carrying the shoulder in front of the forward side of the projection. Then as the forward arm of the lever 42 10 swings to the left, the forward side of the projection 904 engages the shoulder 906, and the arm 908 is actuated to swing the arm 912 upon which it is pivoted, and to swing the arm 558 to which the arm 912 is connected, 15 in a direction to disengage the latch 416 from the catch 420.

Before again starting the sewing operation on a shoe the operator may, if he wishes, 20 disengage the shoe from the sewing mechanism and cause a reverse rotation of the pattern cam shaft to any desired extent so as to permit starting the operation on the shoe back of the point at which the mis-stitch occurred or at the end of the last complete 25 stitch. To do this he moves the jack manually towards the front of the machine to remove the shoe from the sewing mechanism, shifts the shaft 242 longitudinally to reverse the direction of rotation of the pattern cam shaft 176, throws the driving mechanism into operation and after one or more revolutions of the sewing cam shaft operates the catch 420 to stop the machine.

The nature and scope of the invention 35 having been indicated and a machine embodying the several features of the invention in their preferred form having been specifically described, what is claimed is:

1. A sewing machine having, in combination, stitch forming devices, a main shaft from which said devices are operated, devices for stopping the rotation of the shaft, thread controlled means for throwing the stopping devices into operation comprising 40 a movable actuating member having an operative movement during each cycle of operations, mechanism arranged to be actuated by said member for throwing the stopping devices into operation, a controlling device 45 having two positions in one of which it is adapted to prevent the actuation of said mechanism by the actuating member to throw the stopping devices into operation, and in the other of which it is arranged to permit such actuation, a thread actuated arm 50 and connections for moving the controlling device from the second to the first position during each cycle of operations, and means for moving the controlling device from the 55 first to the second position during each cycle.

2. A wax thread sewing machine having, in combination, stitch forming devices including a hook needle, a looper, a take-up, an auxiliary take-up, devices for stopping 60 the machine, thread controlled means for

throwing the stopping devices into operation comprising an actuating member, means for moving said member during each cycle of operations, an arm and connections therefrom for throwing the stopping devices into 70 operation from the movement of the arm, a shoulder formed on said arm adapted to be engaged by said member to actuate the arm, a controlling lever having two positions, in one of which it is adapted to prevent the 75 engagement of said member with the shoulder on the arm, and in the other of which it is adapted to permit such engagement, connections between the controlling lever and the auxiliary take-up for moving said lever 80 from the second to the first position normally during each loop drawing stroke of the take-up, and connections between the controlling lever and said member for moving the controlling lever from the first to 85 the second position after said member has passed the shoulder on the arm during its arm actuating movement in each cycle of operations.

3. A wax thread sewing machine having, 90 in combination, stitch forming devices including a hook needle, a looper, a take-up, an auxiliary take-up, devices for stopping the machine, thread controlled means for throwing the stopping devices into operation comprising an actuating member, means for moving said member during each cycle of operations of the machine, an arm and connections therefrom for throwing 95 said stopping devices into operation arranged to be engaged and actuated by said member, a controlling lever having two positions, in one of which it is adapted to prevent the operative engagement of the 100 arm with said member, and in the other of which it is adapted to permit such engagement, connections between the controlling lever and the auxiliary take-up for moving the lever from the second to the first position normally during each loop drawing 110 stroke of the take-up, and connections between said member and the controlling lever for moving the controlling lever from the first to the second position during each 115 cycle of operations.

4. A wax thread sewing machine having, in combination, stitch forming devices including a hook needle, a looper, a take-up, an auxiliary take-up, devices for stopping the machine, thread controlled means for throwing the stopping devices into operation comprising an actuating member, means for moving said member during each cycle of operations, a projection formed on said member, a pivoted and longitudinally movable arm, and connections for throwing the stopping devices into operation from the longitudinal movement of the arm, a shoulder formed on the arm for engagement with the projection on the actuating member to 125 130

- effect the longitudinal movement of the arm, a controlling lever having two positions, in one of which it is adapted to prevent the engagement of the projection on the actuating member with the shoulder on the arm, and in the other of which it is adapted to permit such engagement, connections between the actuating member and the controlling lever for moving the controlling lever from the first to the second position after the projection on the actuating member has passed the shoulder on the arm during its arm actuating movement in each cycle of operations, and connections between the auxiliary take-up and the controlling lever for moving the same from the second to the first position normally during each loop drawing stroke of the take-up.

5. A wax thread sewing machine having, in combination, stitch forming devices, a work support, a presser foot, a main shaft from which said devices are operated, mechanism for driving the shaft and for stopping the same at a predetermined point in its 20 rotation comprising a high speed driving clutch, a slow speed driving clutch, means for engaging and disengaging the high speed clutch, means for engaging the slow speed clutch when the high speed clutch is thrown 25 out, and for disengaging the slow speed clutch when the shaft reaches stopping position comprising a sleeve mounted on the shaft to rotate with the shaft and to slide longitudinally of the shaft, and carrying 30 one of the members of the slow speed clutch, a cam carried by the sleeve, a lever normally oscillated idly by the cam, a movable lock bolt carrier, a lock bolt movably mounted in the carrier to lock the carrier to the lever to cause movements of the sleeve on the shaft to disengage the clutch, and means actuated by the movement of the lock bolt carrier to lift the presser foot.

6. A wax thread sewing machine having, in combination, stitch forming devices, a work support, a presser foot, a main shaft from which said devices are operated, mechanism for driving the shaft and for stopping the same at a predetermined point in its 40 rotation comprising a high speed driving clutch, a slow speed driving clutch, means for engaging and disengaging the high speed clutch, and connections between the lock bolt carrier and the presser foot for lifting the presser foot from the movement of the carrier as the slow speed clutch is disengaged.

7. A wax thread sewing machine having, in combination, stitch forming devices, a work support, a presser foot, a shaft from which said devices are operated, a clutch for driving the shaft, a sleeve mounted to 45 rotate with the shaft and to slide longitudinally, and carrying one of the members of the clutch, a cam carried by the sleeve, a lever normally oscillated idly by the cam, a movable lock bolt carrier, a lock bolt movably mounted in the carrier to lock the carrier to the lever to cause movements of the sleeve on the shaft to disengage the clutch, and means actuated by the movement of the lock bolt carrier to lift the presser foot.

8. A wax thread sewing machine having, in combination, stitch forming devices, a work support, a presser foot, a main shaft from which said devices are operated, a clutch for driving the shaft, a sleeve mounted to 50 rotate with the shaft and to slide longitudinally, and carrying one of the members of the clutch, a cam carried by the sleeve, a lever normally oscillated idly by the cam, a movable lock bolt carrier, a lock bolt movably mounted in the carrier to lock the carrier to the lever to cause movements of the sleeve to disengage the clutch, a brake for stopping the shaft when the clutch is disengaged, and connections between the lock bolt carrier and the presser foot for lifting the presser foot from the movement of the lock bolt carrier.

9. A wax thread sewing machine having, in combination, stitch forming devices, a work support, a presser foot, a shaft from which said devices are operated, a cam driven by the shaft, a lever normally oscillated idly by the cam, a movable lock bolt carrier, a lock bolt movably mounted in the carrier for locking the carrier to the lever, means for actuating the lock bolt to lock the carrier to the lever upon stopping the machine, and means actuated by the movement of the carrier produced by the movement of the lever when the carrier is locked thereto for lifting the presser foot.

10. A sewing machine having, in combination, stitch forming devices, a work support, a presser foot, means for forcing the presser foot toward the work support to clamp the material, a ratchet connected with the presser foot, a locking pawl for engagement with the ratchet to lock the presser foot in position, means for moving the pawl 100

- out of engagement with the ratchet to unlock the presser foot during each cycle of stitch forming operations, a normally inoperative pawl lifter arranged to act directly on the pawl, a handle connected therewith for manual operation, stop mechanism arranged to stop the machine at a point in a cycle of operations when the pawl is normally in engagement with the ratchet, and means thrown into operation upon stopping the machine for moving the pawl lifter to lift the pawl out of engagement with the ratchet and thereby unlock the presser foot.
11. A sewing machine having, in combination, stitch forming devices, a work support, a presser foot lever, a presser foot mounted on one end of said lever, a ratchet mounted on the other end of said lever, a locking pawl for engagement with the ratchet, means for moving the pawl into and out of engagement with the ratchet during each cycle of stitch forming operations, a pressure lever yieldingly connected with the presser foot lever, a ratchet mounted on the pressure lever, mechanism including a pawl arranged to engage the latter ratchet for actuating the pressure lever to force the presser foot toward the work support, a normally inoperative pawl lifter arranged to act directly on the pawls, a handle connected therewith for manual operation, stop mechanism arranged to stop the machine at a point in a cycle of operations when the pawls are normally in engagement with the respective ratchets, and means thrown into operation upon stopping the machine for moving the pawl lifter to lift the pawls from the ratchets.
12. A sewing machine having, in combination, stitch forming devices, a main shaft from which said devices are operated, a work support, a presser foot, means for forcing the presser foot toward the work support to clamp the material, a ratchet connected with the presser foot, a locking pawl for engagement with the ratchet to lock the presser foot in position, means for moving the pawl out of engagement with the ratchet to unlock the presser foot during each cycle of stitch forming operations, manually operable means for lifting the pawl from the ratchet, and raising the presser foot, stop mechanism acting during the forward rotation of the shaft to stop the machine at a point in a cycle of stitch forming operations when the pawl is normally in engagement with the ratchet, and means thrown into operation by stopping the machine for lifting the pawl from the ratchet, and raising the presser foot.
13. A sewing machine having, in combination, stitch forming devices, a main shaft from which said devices are operated, a work support, a presser foot lever, a presser foot mounted on one end of said lever, a ratchet mounted on the other end of said lever, a locking pawl for engagement with the ratchet, means for moving the pawl into and out of engagement with the ratchet during each cycle of stitch forming operations, a pressure lever yieldingly connected with the presser foot lever, a ratchet mounted on the pressure lever, mechanism including a pawl arranged to engage the latter ratchet for actuating the pressure lever to force the presser foot toward the work support, and mechanism acting during the forward rotation of the shaft to stop the machine at a predetermined point in a cycle of operations and to raise the presser foot as the machine is brought to rest.
14. A sewing machine having, in combination, stitch forming devices, a main shaft from which said devices are operated, a work support, a presser foot lever, a presser foot mounted on one end of said lever, a ratchet mounted on the other end of said lever, a locking pawl for engagement with the ratchet, means for moving the pawl into and out of engagement with the ratchet during each cycle of stitch forming operations, a pressure lever yieldingly connected with the presser foot lever, a ratchet mounted on the pressure lever, mechanism including a pawl arranged to engage the latter ratchet for actuating the pressure lever to force the presser foot toward the work support, stop mechanism acting during the forward rotation of the shaft to stop the machine at a point in a cycle of operations when the pawls are normally in engagement with the respective ratchets, and means operated by stopping the machine to lift the pawls from the ratchets and raise the presser foot.
15. A sewing machine having, in combination, stitch forming devices, a work support, a presser foot, a cam shaft and driving mechanism therefor, means for throwing said mechanism out of operation in stopping the machine, including a cam and normally inoperative connections, and means actuated by said cam through said connections for raising the presser foot.
16. A sewing machine having, in combination, stitch forming devices, a work support, a presser foot, a cam shaft, high speed driving mechanism therefor, low speed driving mechanism thrown into operation in stopping the machine, a cam and normally inoperative devices cooperating with the cam and arranged to be actuated by the cam in stopping the machine for throwing out the low speed mechanism and lifting the presser foot.
17. A wax thread sewing machine having, in combination, stitch forming devices, a work support, a presser foot, a pull-off, and connections controlled by the relative posi-

tions of the work support and presser foot as determined by the thickness of the work for varying the thread-drawing action of the pull-off to cause the pull-off to draw off from the supply during each cycle of operations the proper quantity of thread for the succeeding stitch, and means for adjusting said connections to vary the threaded-drawing action of the pull-off at predetermined points in the sewing of a seam.

18. A wax thread sewing machine having, in combination, stitch forming devices, a work support, a presser foot, a pull-off, and connections controlled by the relative positions of the work support and presser foot as determined by the thickness of the work for varying the thread-drawing action of the pull-off to cause the pull-off to draw off from the supply during each cycle of operations the proper quantity of thread for the succeeding stitch, and means controlled independently of the relative positions of the work support and presser foot for varying the thread-drawing action of the pull-off at predetermined points in the sewing of a seam.

19. A wax thread sewing machine having, in combination, stitch forming devices, a work support, a presser foot, a pull-off, and connections controlled by the relative positions of the work support and presser foot as determined by the thickness of the work for varying the thread-drawing action of the pull-off to cause the pull-off to draw off from the supply during each cycle of operations the proper quantity of thread for the succeeding stitch, a shoe supporting jack, said jack and stitch forming devices being relatively movable to transfer the point of operation about the shoe, and means controlled independently of the relative positions of the work support and presser foot for varying the thread-drawing action of the pull-off at predetermined points in the sewing of a seam.

20. A shoe sewing machine having, in combination, stitch forming devices including a curved hook needle, a work support, a presser foot, a pull-off lever, a presser foot lever, a frame depending from the presser foot lever, an oscillating lever pivoted on the frame and having a slot, a block pivoted on the pull-off lever and operating in the slot, a lever and connections for actuating the oscillating lever, and means for adjusting said connections during the operation of the machine to vary the throw of the pull-off lever.

21. A wax thread sewing machine having, in combination, stitch forming devices, a work support, a presser foot, a pull-off, connections controlled by the relative positions of the work support and presser foot as determined by the thickness of the work for controlling the thread-drawing action of the

pull-off, actuating mechanism for the pull-off comprising a cam lever, a bell crank lever pivoted upon one arm of the cam lever, a connection between the pull-off and the bell crank for oscillating the pull-off, a rock shaft, an arm mounted thereon, a link connecting said arm and the other arm of the bell crank, and means for adjusting the rock shaft to vary the throw of the pull-off.

22. A machine of the class described having, in combination, means for operating on the work, means for feeding the work, a work gage past which the work is fed, and automatically acting mechanism for moving the gage to vary the position of the work relative to the operating means and for adjusting the feeding means to change the length of feed at predetermined points in the operation of the machine on the work.

23. A wax thread sewing machine having, in combination, stitch forming devices, work feeding means, a work gage, and automatically acting mechanism for moving the gage to vary the position of the seam relative to the edge of the work and for adjusting the feeding means to change the length of feed at predetermined points in the formation of the seam.

24. A wax thread sewing machine having, in combination, stitch forming devices, work feeding means, a gage for determining the position of the seam relative to the edge of a shoe sole, and automatically acting mechanism for moving the gage forwardly and for shortening the feed in passing from the shank to the forepart of the shoe sole and for retracting the gage and lengthening the feed in passing from the forepart to the shank.

25. A shoe sewing machine having, in combination, stitch forming devices including a curved hook needle, a work support, a presser foot, a feed slide, an upright thereon, a shaft journaled in the upright, an edge gage mounted on the upper end of the shaft to swing over the work support, a horizontal shaft journaled in the feed slide, gearing connecting the lower end of the first shaft and the inner end of the second shaft, and means acting on the outer end of the second shaft for turning the second shaft to effect the adjustment of the gage.

26. A shoe sewing machine having, in combination, stitch forming devices including a curved hook needle, a work support, a presser foot, a feed slide, an upright thereon, a shaft journaled in the upright, an edge gage mounted on the upper end of the shaft to swing over the work support, a horizontal shaft journaled in the feed slide, gearing connecting the lower end of the first shaft and the inner end of the second shaft, and means acting on the outer end of the second shaft for turning the second shaft to effect the adjustment of the gage comprising a gear

segment fixed to the outer end of the latter shaft, a pivoted lever, a gear segment carried by the lever and meshing with the first gear segment, a cam shaft, a cam carried thereby, and connections between the cam and the lever for actuating and controlling the lever to advance and retract the gage in timed relation to the feeding of the shoe.

27. A wax thread sewing machine having, in combination, stitch forming mechanism, work feeding means, a feed regulating lever, and automatically acting mechanism for moving the lever in one direction to shorten the feed in passing from the shank to the forepart of a shoe sole and for moving the lever in the opposite direction to lengthen the feed in passing from the forepart to the shank.

28. A machine of the class described having, in combination, means for operating on the working, work feeding means, mechanism for changing the relative positions of the operating means and the work to present the work properly to the operating means as the point of operation is transferred along the work, and automatically acting mechanism for changing the length of feed with relation to the operating means at predetermined points in the operation of the machine on the work.

29. A wax thread sewing machine having, in combination, stitch forming devices, work feeding means, a feed regulating lever, mechanism for changing the relative positions of the operating means and the work to present the work properly to the operating means as the point of operation is transferred along the work, and automatically acting mechanism for moving said lever to change the length of feed at predetermined points in the formation of the seam.

30. A machine of the class described having, in combination, means for operating on the work, work feeding means, a feed regulating lever, mechanism for changing the relative positions of the operating means and the work to present the work properly to the operating means as the point of operation is transferred along the work, and automatically acting mechanism for moving said lever to change the length of feed with relation to the operating means at predetermined points in the operation of the machine on the work.

31. A machine for operating on shoes having, in combination, means for operating on a shoe, a shoe supporting jack, means for feeding the shoe continuously past the operating means so as to perform a continuous operation on the shoe bottom, said jack and operating means being relatively movable to transfer the point of operation about the shoe, and mechanism acting automatically to change the rate of feed of the shoe at predetermined points in the operation.

32. A machine for operating on shoes hav-

ing, in combination, means for operating on a shoe and a shoe supporting jack relatively movable to transfer the point of operation about the shoe, a movable work gage, and means active throughout the operation for moving the gage.

33. A machine for sewing shoes having, in combination, stitch forming devices and a shoe supporting jack relatively movable to transfer the point of operation about the shoe, a work gage, and automatically acting mechanism for moving the gage to vary the position of the seam relative to the edge of the shoe bottom at predetermined points in the formation of the seam.

34. A machine for sewing shoes having, in combination, stitch forming devices and a shoe supporting jack relatively movable to transfer the point of operation about the shoe, shoe feeding means and mechanism acting automatically to adjust the feeding means to change the length of feed at predetermined points in the formation of the seam.

35. A wax thread sewing machine having, in combination, stitch forming devices, a shaft from which said devices are operated, a thread tension device, a high speed driving clutch, a slow speed driving clutch, means for engaging and disengaging the high speed clutch, means for engaging the slow speed

clutch when the high speed clutch is thrown out and for disengaging the slow speed clutch when the shaft reaches stopping position, comprising a sleeve upon which the movable member of the slow speed clutch is mounted, a cam carried by the sleeve, a lever normally oscillated idly by the cam, a movable lock bolt carrier, a lock bolt movably mounted in the carrier for locking the carrier to the lever to cause the engagement and disengagement of the slow speed clutch, and connections between the lock bolt carrier and the tension device for actuating the tension device to relieve the tension on the thread from the movement of the carrier as the slow speed clutch is disengaged.

36. A wax thread sewing machine having, in combination, stitch forming devices, a shaft from which said devices are operated, a thread tension device, a high speed driving clutch, a slow speed driving clutch, means for engaging and disengaging the high speed clutch, means for engaging the slow speed

clutch when the high speed clutch is thrown out, and for disengaging the slow speed clutch when the shaft reaches stopping position, comprising a sleeve upon which the movable member of the slow speed clutch is mounted, a cam carried by the sleeve, a lever normally oscillated idly by the cam, a movable lock bolt carrier, a lock bolt movably mounted in the carrier for locking the carrier to the lever to cause the engagement and disengagement of the clutch, a brake, and connections between the lock bolt carrier

and the brake and between the carrier and the tension device for actuating the tension device to relieve the tension on the thread, and for engaging the brake from the movement of the carrier as the slow speed clutch is disengaged.

37. A wax thread sewing machine having, in combination, stitch forming devices, a shaft from which said devices are operated, a thread tension device, a friction clutch for driving the shaft comprising cooperating clutch members, one of which is movable to engage and disengage the clutch, a sleeve upon which the movable member of the clutch is mounted, a cam carried by the sleeve, a lever normally oscillated idly by the cam, a movable lock bolt carrier, a lock bolt movably mounted in the carrier to lock the lever to the carrier to effect the disengagement of the clutch, and means actuated by the movement of the lock bolt carrier as the clutch is disengaged to actuate the tension device to relieve the thread of tension.

38. A wax thread sewing machine having, in combination, stitch forming devices, a shaft from which said devices are operated, a thread tension device, a friction clutch for driving the shaft comprising cooperating clutch members, one of which is movable to engage and disengage the clutch, a sleeve upon which the movable member of the clutch is mounted, a cam carried by the sleeve, a lever normally oscillated idly by the cam, a movable lock bolt carrier, a lock bolt movably mounted in the carrier to lock the lever to the carrier to effect the disengagement of the clutch, a brake for stopping the shaft when the clutch is disengaged, and connections between the lock bolt carrier and the tension device for actuating the tension device to relieve the thread of tension as the clutch is disengaged.

39. A wax thread sewing machine having, in combination, stitch forming devices, a main shaft from which said devices are operated, a thread tension device, a cam rotating with the shaft, a lever normally oscillated idly by the cam, a movable lock bolt carrier, a lock bolt movably mounted in the carrier for locking the carrier to the lever, means for actuating the lock bolt to lock the

carrier to the lever upon stopping the machine, and means actuated by the movement of the carrier to actuate the tension device to relieve the thread of tension as the machine is stopped.

40. A wax thread sewing machine having, in combination, stitch forming devices, a work support, a presser foot, and mechanism for automatically stopping the machine and lifting the presser foot at a predetermined point in the formation of the seam.

41. A wax thread sewing machine having, in combination, stitch forming devices, a work support, a presser foot, a tension device, and mechanism for automatically stopping the machine, lifting the presser foot and actuating the tension device to release the tension on the thread at a predetermined point in the formation of the seam.

42. A machine for operating on shoes having, in combination, means for operating on a shoe, a shoe supporting jack movable to transfer the point of operation about the shoe, a fixed guiding member engaging the shoe in the crease between the upper and welt, an edge gage to bear against the edge of the shoe sole, and mechanism acting automatically during the operation on the shoe to move the edge gage into and out of gaging position.

43. A machine for operating on shoes having, in combination, means for operating on a shoe, a shoe supporting jack movable to transfer the point of operation about the shoe, a guiding member engaging the shoe to guide the shoe during a portion of the operation, a movable gage, and mechanism acting automatically during the operation on the shoe to move said gage into and out of gaging position.

44. A machine for operating on shoes having, in combination, means for operating on a shoe, a shoe supporting jack movable to transfer the point of operation about the shoe, an edge gage mounted to bear against the edge of the sole of a shoe supported upon the jack, and mechanism acting automatically during the operation on the shoe to move the edge gage into and out of gaging position.

LAURENCE E. TOPHAM.
